APPARATUS FOR HARDENING AND DRAWING FERROUS METALLIC ARTICLES

Frederic O. Hess, Fred Maud, and William B. Troupe, Philadelphia, Pa., assignors to Selas Corporation of America, Philadelphia County, Pa., a corporation of Pennsylvania

Application February 8, 1947, Serial No. 727,410

1 Claim. (Cl. 266—4)

1

The general object of the present invention is to provide an improved apparatus for heat treatment. More particularly, the object of the present invention is to provide an apparatus for hardening and tempering steel-like bodies by heating, quenching and reheating them in a series of intermittent operations performed in a predetermined sequence and during predetermined time intervals.

A more specific object of the invention is to provide apparatus including a rotatable work support comprising one or more rotatable work supporting dials or wheel-like members, each having a plurality of work holding seats at or adjacent and distributed along its periphery for holding a plurality of bodies distributed about its axis of rotation to be successively subjected to heat treating operations. The apparatus also includes means for intermittently turning said work support about its axis through successive small angular steps.

In a preferred form of the invention, the work support comprises two dials or rotating members of the character mentioned. One of said dials may be called the hardening dial as it is associated with heating and quenching apparatus so disposed and arranged that the ends of each work piece will be progressively heated up to a temperature in excess of its critical temperature and then cooled and hardened as the wheel turns the seat carrying the work piece from a loading station to an unloading station which may be coincident with or slightly to the rear of the loading station. The second dial may be called a drawing or tempering dial and may be similar in construction and in the general mode of its use to the first mentioned dial, but is associated with work re-heating and cooling means appropriate to the lower temperatures and less abrupt changes in temperatures which are suitable for use in drawing or tempering work pieces previously hardened while supported in the first mentioned dial.

Our improved method is characterized by the regulation of the rates at which heat is supplied to and removed from work pieces during successive equal periods of time, so as to subject each work piece to the appropriate temperature cycles required for efficient and uniform hardening, and drawing or tempering of the articles treated.

The various features of novelty which characterize our invention are pointed out with particularity in the claim annexed to and forming a part of this specification. For a better under-

2

standing of the invention, however, its advantages, and specific objects attained with its use, reference should be had to the accompanying drawings and descriptive matter in which we have illustrated and described preferred embodiments of the invention.

Of the drawings:

Fig. 1 is an elevation of one form of heat treating apparatus with parts broken away and in section;

Fig. 2 is an elevation taken to right angles to Fig. 1, and partly in section on the line 2—2 of Fig. 1 and with parts broken away;

Fig. 3 is an elevation taken at right angles to Fig. 1 with parts broken away and partly in section on the line 3—3 of Fig. 1;

Fig. 4 is a plan view of a modified form of heat treating apparatus;

Fig. 5 is an elevation of the apparatus shown in Fig. 4, and

Fig. 6 is an elevation on a larger scale than Fig. 5 and illustrates the construction of parts omitted in Fig. 5 to simplify that figure.

In Figs. 1-3 of the drawings we have illustrated, by way of example, apparatus for hardening and tempering the ends of machinists' hammers or analogous work pieces. The apparatus shown in Figs. 1 and 2 comprise a supporting framework A on a base portion of which is mounted a metal casing or housing structure comprising a rectangular lower box-like structure B and three upper arch or hood portions B', B² and B³ rising from the upper side of the box-like body portion of the housing. The housing portions B' and B³ are located above opposite end portions of the housing body B, and the portion B² is located midway between the portions B' and B³. The framework A of the apparatus comprises uprising pillar portions A', in which is journalled a horizontal shaft C with one end beneath the hood portion B' and its other end beneath the hood portion B³.

Rigidly secured to the shaft C are two work supporting dial or wheel-like member D and DA, the dial D being approximately midway between the hoods B' and B², and the dial DA being approximately midway between the hoods B² and B³. As shown, dial member D supports work pieces d, in the form of hammer heads with peens, during the operation of simultaneously hardening the two ends of said heads, and the dial DA supports the same hammer heads while the latter are being tempered. The two dials may thus be identical in form and in construction, each comprising a series of work support-

ing units D' distributed about the periphery of, and secured as by bolts D² to a wheel center D³. Each unit D' is formed with a seat D⁴ for the intermediate portion of a hammer head, said seat comprising a slot extending through the part D' and centering pin D⁵ adapted to extend through the handle opening in the hammer head. The work supporting units D' may advantageously be castings of heat resistant metal such as chrome steel, and the wheel center D³ may advantageously be made of bronze to avoid corrosion as a result of its continuous contact with quenching liquid.

To anchor the hammer heads in place in the dial while the latter makes a substantially complete revolution, suitable retaining means are needed. As shown, a separate retaining device D⁶ is associated with each of the dials D and DA. Such device D⁶ is a metallic bar or strip bent into an arc fitting closely against the portion of the periphery of the corresponding dial below the level of the axis of the shaft C and having short vertical end portions D⁷ extending up from said level.

The shaft C, and thereby the dials D and DA, are given intermittent angular movements in the direction of the arrow shown in Fig. 3, by a pawl and ratchet mechanism comprising a ratchet wheel E secured to one end of the shaft C and provided with a suitable multiplicity of teeth or shoulder portions E'. The number of teeth E' is equal to the number of work holding seat parts at the periphery of each dial. In the particular arrangement shown, by way of example, in Figs. 1-3, each of the dials D and DA has twelve peripheral work seats, and the ratchet wheel E is formed with twelve teeth or shoulders E' and is given a complete revolution in twelve successive angular steps, each of 30°. The wheel E is given its successive angular adjustments by means of a pawl F' pivoted to one end of a ratchet lever F which is mounted for oscillation about the axis of the shaft C. The lever F has its second end connected by a link F² to a plunger F³ working in a hydraulic cylinder F⁴. The latter has its lower end pivotally connected to the base of the framework A through a fulcrum pin F⁵. Oil, or other fluid under pressure, is admitted to and discharged from the cylinder F⁴ through inlet and outlet ports F⁶ and F⁷, respectively, by a suitable electric valve mechanism operating intermittently at predetermined intervals under the control of an electric timing system. Since the specific construction of the valve mechanism and timing system form no part of the present invention and may be of well known commercial types, they need not be illustrated or described herein.

As shown, the ratchet lever F comprises two similar plate-like parts F at opposite sides of the wheel E and each surrounding a corresponding hub-like portion E² of the ratchet wheel E which is keyed to the shaft C. As is indicated in Fig. 3, the angular travel of the pawl F' between its normal position, shown in full lines in Fig. 3, and its dotted line position shown in Fig. 3, at which it completes an angular advancing movement of the ratchet wheel E, is considerably greater than the annular distance between two successive teeth E' of the wheel E. In consequence, a substantial initial portion of each movement of the pawl F' away from its position shown in full lines in Fig. 3, is an idle movement, insofar as its effect on the angular position of the ratchet wheel E is concerned. However, dur-

ing such initial portion of the movement of the pawl F', the ratchet lever operates to effect a gas burner position adjustment, as is hereinafter described.

To insure that the shaft C will be maintained stationary in the respective positions into which it is adjusted by the successive counterclockwise movements of the ratchet lever F as seen in Fig. 3, the shaft C is provided with a suitable locking device. The latter, as shown in Fig. 1, comprises a non-rotatable braking element G which is formed with an aperture through which passes the end portion of the shaft C remote from the ratchet wheel E. A spring G² holds the inner side of the element G in frictional contact with a brake disc G' secured to the shaft C. The spring G² acts between the member G and a collar C' secured to the end of the shaft C. The member G and disc G' may be faced with brake lining material G³.

As shown in the drawings, each work piece d is put in place in, and removed from its seat D⁵ in the dial D while said seat is moving through a loading and unloading station intermediate the ends of the quadrant of its path of movement extending from the level of the axis of the shaft C to the highest level attained by the seat. During its movement through the succeeding quadrant of its path of movement, the work piece is subjected, during three successive intervals, to the heating effect of three heating elements H, H' and H² at the side of the disc D adjacent the hood B' and spaced 30° apart about the axis of the shaft C. While the burner heating elements H, H' and H² are thus acting successively on one end of the work piece d, three heating elements HA, HA', and HA² act on the other end of said work piece. The six heating elements thus acting on each work piece mounted on the dial D, are gas burners, preferably supplied with a combustible mixture of some commercially available fuel gas and air, ordinarily in approximately the ratio required for complete combustion. Associated with the dial DA are burners h, h' and h² at one side, and burners ha, ha' and ha² at the opposite side of the dial. As shown, the burners h and ha are in axial alignment with the burners H and HA, the burners h' and ha' are in axial alignment with the burners H' and HA', and the burners h² and ha² are located in axial alignment with the burners H² and HA².

As shown, the burners H, H' and H² are supported by a member H³ comprising a plate-like portion normally in register with an opening in the adjacent side wall of the hood B'. Similarly, the burners HA, HA' and HA² are supported by a support HA³ in register with an opening in the adjacent side wall of the hood B². The burners h, h' and h² are supported by a supporting member h³, and the burners ha, ha' and ha² are supported by a member ha³, and the members h³ and ha³ are in register with openings in the adjacent sides of the hoods B³ and B², respectively.

65 The burner supports HA³, h³, ha³ may all be stationary, but as shown, the burner support H³ is mounted in the framework A for movement between normal and retracted positions, shown in full and dotted lines respectively, in Fig. 1. The support H³ is part of a structural element formed with an opening through which the shaft C loosely extends, and pivoted to turn about a pintle H⁴ mounted in the supporting framework A at the opposite side of the shaft C from the burners H, H' and H². In the normal position

of the support H^3 , the burners H , H' and H^2 are so close to the dial D that the adjacent ends of the work pieces d in alignment with the respective burners, are within the combustion spaces of the latter. When the support H^3 is in its dotted line position, the burners H , H' and H^2 are displaced far enough from the dial D to provide clearance between the ends of the burners and the adjacent work pieces as the dial is angularly advanced or indexed, during the final portion of the working stroke of the ratchet lever F . The burners H , H' and H^2 are the only burners associated with the dials D and DA into which portions of the aligned work pieces extend at any time. With portions of the work pieces normally within the combustion chambers of the burners H , H' and H^2 , those portions may be supplied with heat at a more rapid rate than the work piece portions heated by the other burners. This is practically desirable when the work pieces are so shaped, as are the hammer head pieces d shown in Fig. 1, as to require substantially more heat during the hardening operation than is required in any other heating action to which the work pieces are subjected.

The support H^3 is moved away from the dial D preparatory to each dial indexing, or angular advancement. To this end, in the construction shown, the support H^3 is formed with a flange H^5 in the form of a section of a hollow cylinder substantially coaxial with the shaft C . A cam slot H^6 is formed in the flange H^5 and has an upper portion inclined to a plane transverse to the shaft C , and a lower portion substantially parallel to said plane. An arm F^{10} secured to the lever F carries a roller F^{11} which has its axis substantially radial to the shaft C and extending through and fitting in the slot H^6 . The roller F^{11} moves through the inclined upper portion of the slot and thereby turns the support H^3 about the pivot pin H^4 into its retracted position as the lever F turns counter clockwise as seen in Fig. 3 through the initial portion of its movement in which the pawl F' moves into the position in which it engages the adjacent tooth E' . In consequence, the burners H , H' and H^2 are moved to the left of the work pieces mounted in the dial D , before the continuing counter clockwise movement of the lever F operates through the pawl F' and tooth E' to give the dial an indexing movement. During said continuing movement and during an initial return movement of the lever F , the roller F^{11} moves along the lower straight portion of the cam slot without giving movement to the support H^3 . During the final portion of the return stroke of the lever F , the roller F^{11} moves into the upper inclined portion of the slot and thereby returns the burner support H^3 to its normal position.

The various burners H , H' — h' , h^2 are supplied with combustible mixture through individual and individually regulable branches I of a piping system which includes a main supply pipe I^5 . The piping system ordinarily includes the usual accessories such as fire checks, as well as throttling valves which permit of separate regulation of the rates at which combustible mixture is supplied to each group of valves located at the same side of the same dial. Inasmuch as said piping system embodies nothing claimed as novel herein, further descriptive references thereto is believed to be unnecessary. The various burners may be of commercially available types. Preferably each burner includes a combustion

chamber with an outlet at its end adjacent the work and formed with a plurality of small channels opening into the combustion chamber at its rear end. To secure the rapid heating action desirably supplied by the burners associated with the dial D , each of those burners may advantageously be of the type disclosed in Hess Patent 2,367,119 of January 9, 1945, in which the outlet from the combustion chamber is restricted so that an excessive atmospheric pressure may be maintained in the combustion chamber. The burners H , H' and H^2 may have the outer ends of their restricted outlet passages enlarged to receive work end portions. The burners associated with the dial DA may well be of the type disclosed in the Hess Patent 2,103,365 of December 28, 1937, granted on the application of one of the applicants herein.

The lower portion of the dial D extends into a quenching liquid bath held in a tank J so that as each work piece moves downward away from the aligned burners H^2 and HA^2 it dips into a quenching bath and may well be immersed therein during the time required for a third or a quarter of a revolution of the dial D . After moving through the quenching bath, each work piece passes upward into the previously mentioned loading and unloading station.

After the work piece has passed from the quenching bath into said loading and unloading station, the work piece thus removed from the dial D is promptly placed in a work seat of the dial DA , after the removal from that work seat of a work piece which has just completed a revolution about the shaft C while mounted in the tempering dial DA . During the period following the removal of the last mentioned work piece from its seat in the dial D , and prior to the movement of the seat into heating relation with the burners H and HA , a fresh work piece is mounted in said seat. Each work piece inserted in a seat D^4 in the dial D is progressively heated at a rapid rate from its initial temperature which may be that of the atmosphere, to a temperature suitably related to the appropriate critical temperature for the work piece material and hardening operation required, while being acted upon successively by the burners H and HA , H' and HA' , H^2 and HA^2 . Thereafter, the work piece is cooled at a suitably rapid rate while immersed in the quenching bath in the tank J .

The rate at which a work piece in either of the dials is heated up may be regulated by varying the rate at which the combustible mixture is supplied to the different burners, and in some cases by varying the composition of said mixture. The rate at which the work pieces are heated up may also be regulated by varying the frequency with which the ratchet lever F is oscillated to produce corresponding angular advances of the wheel E and thereby of the dials D and DA . The rate at which the work piece is cooled in the tank J may be varied, when necessary, by varying the condition or character of the quenching liquid bath in the tank J , and in particular by regulating the agitation of the bath liquid in immediate proximity with the work. Such regulation may be effected by discharging recirculated and make up bath liquid into the bath in jets directed against each work piece while in its initial stationary position in bath.

As previously indicated, the frequency of the actuation of the hydraulic cylinder F^2 may be varied by the adjustment of the automatic electric timing system which may be of commercial

form and which directly controls the energization and deenergization of an electromagnetic valve controlling the supply of working fluid to, and its discharge from the cylinder F².

As will be apparent to those skilled in the art, the general principles of the present invention may be utilized in, and by means of apparatus widely differing in form from the apparatus shown in Figs. 1, 2 and 3. One such alternative form of apparatus is shown, by way of example, in Figs. 4, 5 and 6. The apparatus shown in the last mentioned figures is especially devised for use in hardening and drawing the cutting ends *dd* of chisels L, though such apparatus can be used with little or no modification for other heat treating purposes. The apparatus shown in Figs. 4, 5 and 6 comprises a work holder in the form of a horizontal, circular table DB carried at the upper end of a central vertical shaft CB, which is intermittently rotated to move each chisel L mounted in the work holder successively from a loading and unloading station through a hardening burner station, and thence through an arc shaped quenching zone JA extending around the axis of the shaft CB for something more than 90°, and thence into a reheating station and thence back to the loading and unloading station.

As shown, the work supporting table DB is formed with a plurality of trough-like seats D¹⁵ equally spaced about the axis of the shaft CB, and extending radially away from the axis of rotation of the work support, each adapted to receive a radially extending chisel L between uprising parts D¹⁶ by an individual retaining device D¹⁷ shown as a pivoted arm having one end down turned and engaging the chisel or other work piece and pivoted to turn about a horizontal pintle D¹⁸ carried by a bracket D¹⁹ external to the trough. A helical spring D²⁰ wound about the pintle carrying the clamping part biases the latter for movement into engagement with the work piece mounted in the support. The clamping arm D¹⁷ is provided with a lateral extension D²¹ serving as a handle for raising the clamping bar to facilitate the insertion and removal of work.

When a chisel L mounted in one of the seats D¹⁵ is at the hardening station, the cutting end *dd* of the chisel is received between the upper and lower burners HC and HC', respectively, which are in coaxial alignment and face one another, said burners are adapted to discharge hot products of combustion against the upper and lower sides of the chisel as required to heat the latter to a hardening temperature. With the work table provided with 8 equally spaced work seats D¹⁵, as shown, the work table is given angular advance movements of 45° each, so that 8 different work supports are successively advanced from the loading station into the hardening station in each complete rotation of the work supporting table DB. The shaft CB, and thereby the table DB, may be intermittently advanced by suitable mechanism which may well comprise a pawl and ratchet mechanism similar to that employed to angularly advance the dials D and DA of Figs. 1-3. As will be apparent, the frequency with which the angular advancing movements of the tables are repeated must be suitably related to the heating effect of the burners HC and HC' to insure that each chisel end is heated to the required hardening temperature while between the burners HC and HC'.

At the conclusion of the heating action to which

each chisel is subjected while between the burners HC and HC', the chisel is moved away from the hardening station and into the quenching zone JA. That zone comprises the space within the walls of a quenching chamber in which water or other quenching fluid is sprayed onto the chisel. The heated end of the chisel extends into the quenching chamber through a horizontal slot JA' in the curved wall of the chamber adjacent the periphery of the rotating table DB. As shown, the angular extent of the quenching zone is such that the end portions of the three chisels supported in three adjacent work seats D¹⁵ are within the zone at the same time, and each of the three chisel ends is in position to receive the cooling liquid spray discharged through a corresponding one of three spray liquid supply pipes JA², JA³, and JA⁴. As indicated in Fig. 4, a common receptacle is provided to collect the liquid discharged by the pipes JA² and JA³, and a separate receptacle is provided to collect the liquid discharged by the pipe JA⁴. This permits the pipes JA² and JA³ to discharge quenching oil while the pipe JA⁴ discharges water which washes the oil off the work pieces.

From the quenching zone, each chisel is moved into a reheating station in which the chisel extends between the upper and lower aligned reheating burners HD and HD' which are adapted to heat the chisel end to a suitable drawing temperature during the period in which the chisel is between the last mentioned burners. From the reheating station at which the burners HD and HD' are located, each chisel is returned to the loading and unloading station by three successive angular movements of the table DB. The time required for the movement of each chisel from the reheating station to the loading and unloading station is ample for the cooling of each chisel down to a suitable discharge temperature. The burners HC, HC', HD and HD' may be of the same general types as the burners shown in Fig. 1.

As will be apparent to those skilled in the art, the method of hardening and drawing work pieces when practiced by the use of either form of apparatus illustrated herein, is characterized by the simplicity and accuracy with which the work pieces are heated rapidly and uniformly to the required temperatures by the combustion of gas which may be ordinary city gas, natural gas or some other commercially available fuel gas, and is further characterized by the practical simplicity and effectiveness of the apparatus and its capacity for regulation.

While in accordance with the provisions of the statutes, we have illustrated and described the best forms of embodiment of our invention now known to us, it will be apparent to those skilled in the art that changes may be made in the form of the apparatus disclosed without departing from the spirit of our invention as set forth in the appended claim, and that in some cases certain features of our invention may be used to advantage without a corresponding use of other features.

Having now described our invention, what we claim as new and desire to secure by Letters Patent, is:

Heat treating apparatus including in combination a shaft, a plurality of members thereon having substantially aligned means at the peripheries thereof for holding articles to be heat treated, a plurality of separate heating means, means to mount said heating means to heat articles carried by said members at a plurality of heating

stations, mechanism to rotate intermittently said shaft and members to move the articles carried thereby past the heating stations in equal increments of advance interposed by equal intervals of time during which the articles are stationary, quenching means mounted to quench the articles carried by one of said members at a station subsequent to said heating stations, some of said heating means being operable to surround a portion of said articles, and means operated by said rotating means and in synchronism therewith to move said some of said heating means out of and into heating position as said members are being rotated.
